UNITED STATES PATENT OFFICE

168,974

FLUORESCENT LIGHTING FIXTURE

Joseph H. Spaulding, Lakeside Park, Ky.

Application October 30, 1952, Serial No. 22,049

Term of patent 14 years

(Cl. D48—23)

To all whom it may concern:

Be it known that I, Joseph H. Spaulding, a citizen of the United States, residing at Lakeside Park, county of Kenton and State of Kentucky, have invented a new, original, and ornamental Design for a Fluorescent Lighting Fixture, of which the following is a specification, reference being had to the accompanying drawings, forming part thereof.

Fig. 1 is a perspective view of a fluorescent lighting fixture showing my new design.

Fig. 2 is a bottom plan view thereof.

Fig. 3 is a top plan view; and

Fig. 4 is an end elevational view.

I claim:

The ornamental design for a fluorescent lighting fixture, as shown.

JOSEPH H. SPAULDING.
